reflected in an individual's personality and may also be expressed in the individual's world and in products the individual creates with it. For example, certain types of action can also be used to express individuality, such as the choice of clothing, the way one dresses, the way one acts, and the way one speaks.

Since I had our last time with the family here, the time has passed like a dream. I am so glad that we have the opportunity to go to the beach and the lake. I am so happy to be with my family and friends. I am so grateful for the time we have together.

UNITED STATES PATENT OFFICE

2,609,941

COUPLER LOCK LIFTER TOGGLE LINK

James N. Borland, Chicago, Ill., assignor to
Standard Railway Equipment Manufacturing
Company, Chicago, Ill., a corporation of Dela-
ware

Application October 17, 1949, Serial No. 121 766

4 Claims. (Cl. 213—127)

¹³ The first name of the author is omitted.

This invention relates to improvements in railway car couplers and more particularly to an improvement in the lock lifter toggle link for operating the lock of said couplers.

In the present standard "E" bottom operated couplers a toggle link is connected at one end to the bottom leg of the lock and the rotor lever is connected at one end to the other end of the toggle link and at the other end is pivotally connected for rotary motion on a lug at the rear of the coupler, said rotor lever having an opening therethrough intermediate its ends for connection to the hooked end of an associated operating rod. Rotation of the rod causes the rotor lever to swing on its pivot and thereby lift the toggle link which raises the lock and unlocks the coupler. When the operating rod is rotated the toggle link must move upwardly through an opening in the bottom of the coupler, which opening allows but a minimum of clearance for the toggle link and associated rotor lever and, due to various conditions of wear of the coupler operating mechanism parts the rotor lever not infrequently strikes the bottom wall of said opening in its upward travel, thereby rendering impossible the proper functioning of the coupler operating mechanism.

It is, therefore, the principal object of the invention to provide a toggle link having an external contour forming a cam surface to direct the toggle link toward the center of the coupler opening and thereby guide the rotor lever into the opening free and clear of the side walls forming said opening.

Other objects and advantages of the invention will appear in the following description of the invention.

Referring now to the accompanying drawing forming part of this application, wherein like reference characters indicate like parts:

Figure 1 is a side elevation of the improved lock lifter toggle link, showing its attachment to associated parts of a railway car coupler in rest position, the coupler head being shown in central vertical section.

Figure 2 is a view similar to Figure 1 showing the parts in raised position.

Figure 3 is a side elevation of the improved lock lifter toggle link and fragments of the associated coupler parts showing the toggle link in rest position.

Figure 4 is a similar view to Figure 2 but showing the parts in elevated position.

The lower portion of a standard type "E" bottom operated railway car coupler is shown in section at 1, and the essential parts of the cou-

pler, insofar as the invention is concerned, are the knuckle thrower 2, lock 3, toggle link 4, and rotor lever 5, all of which are pivotally joined one to the other.

The rotor lever 5 is of the common rotary type having a hooked end 6 which hooks over trunnion 7 and the other end is bifurcated and pivoted, as at 8, to one end of the improved toggle link 4. The other end of toggle link 4 is provided with a laterally extending pintle 9 which extends through the diagonally disposed elongated hole 10 in lower end of lock 3. This arrangement of parts is old in the art.

15 The rotor lever 5 is provided intermediate its ends with a transverse hole therethrough indicated at 11, through which the hooked end 12 of a coupler operating rod 13 extends, the free end of said end 12 bearing against shoulder 14 formed in lower surface of the rotor lever 5. 20 Thus upon clockwise rotation of said rod, as viewed in Figures 1 and 2, rod 13 revolves rotor lever 5 about trunnion 7, pushing upwardly on toggle link 4, which in turn raises lock 3 and unlocks the coupler.

25 The lower portion of the lock 3, the toggle link 4 and portion of rotor lever 5 which is pivotally connected to toggle link 4, must move vertically through the hole 14' in the bottom of the coupler, which hole 14' is restricted both in width and
30 length to allow movements of the parts therethrough with but limited tolerance. Because of various conditions of wear, the pivotal connections of the parts become loose, which parts then tend to buckle sidewise during operation, resulting in one or the other of the bifurcated ends 15 of the rotor lever bumping against the bottom edge of the walls of hole 14', which, of course, positively prevents further upward movement of the parts. To overcome this difficulty there is
35 integrally formed on the surface of the toggle link 4, just above the bifurcated end of rotor lever 5, a laterally projecting cam lug 16, which extends outwardly under the pintle in the path of the bottom edge of walls of said hole 14' and overhangs the upper end of one of the bifurcated portions of the rotor lever so that if the parts of
40 said mechanism are worn the cam surface on the end of said lug would strike the edge of said walls and direct the parts upwardly into said hole, preventing contact of said ends 15 with said walls.
45 In this manner the rotary lock lift lever of necessity must enter the lock hole in the bottom of the coupler.

I claim;

- 55 1. In a railway car coupler having a lock opening therein, a lock within said opening, a rotor

lever pivotally connected at one end to said coupler, the other end of said lever being bifurcated, a toggle link pivotally connected at its lower end between the bifurcated portion of the rotor lever, and having a pintle extending laterally of said coupler for pivotal connection to said lock, a lug adjacent the lower end of said toggle link and under said pintle which overhangs the upper end of one of said bifurcated portions, said lug having a cam surface engageable with a wall defining said opening, whereby in rotating said rotor lever said cam surface insures entry of the bifurcated end of said lever in said opening.

2. In a railway car coupler having a lock opening, a lock within said opening, a rotor lever bifurcated at one end and pivotally connected at its other end to said coupler, a toggle link having a pintle at one end extending laterally of said coupler, for pivotal connection to said lock, said link being pivotally connected to said rotor lever between said bifurcated portions, a lug projecting laterally from said toggle link, under said pintle, and overhanging the end of one of said bifurcated portions, said lug having a cam surface engageable with a wall defining said opening, whereby in rotating said rotor lever, said cam surface insures entry of the bifurcated end of said lever in said opening.

3. A toggle link for a railway car coupler having an opening therein, said link having a pintle

at one end for pivotal connection to a coupler lock, an opening at the other end for pivotal connection to a rotor lever, and a lug integrally formed on and intermediate the ends of said link and projecting from the same side as said pintle, said lug having a cam surface slidably engageable with a wall of said opening to guide movement of said rotor lever into said opening.

4. A toggle link for a railway car coupler having an opening therein, said link having a laterally projecting pintle at one end for pivotal connection to a coupler lock, an opening at the other end for pivotal connection to a rotor lever, and a lug projecting laterally therefrom in the direction of and under said pintle, said lug having a cam surface slidably engageable with a wall of said opening to guide movement of said rotor lever into said opening.
